CLAIM

The ornamental design for a knob for oven range, as shown and described.

DESCRIPTION

1. Knob for oven range
- 1.1 : Perspective
- 1.2 : Front
- 1.3 : Back
- 1.4 : Left
- 1.5 : Right
- 1.6 : Top
- 1.7 : Bottom

(Continued)

The parts shown by means of broken lines in the reproductions are not part of the claimed design.

1 Claim, 7 Drawing Sheets
